US0D1107918S

(12) **United States Design Patent** (10) Patent No.: **US D1,107,918 S**
(45) Date of Patent: ** Dec. 30, 2025

(54) **BLOOD PRESSURE MEASURING APPARATUS**

(71) Applicant: **Andon Health Co., Ltd.**, Tianjin (CN)

(72) Inventors: **Zhiqing Liu**, Tianjin (CN); **Lina Wang**, Tianjin (CN); **Chunpo Liu**, Tianjin (CN)

(**) Term: **15 Years**

(21) Appl. No.: **35/522,051**

(22) Filed: **Aug. 6, 2024**

(80) **Hague Agreement Data**

Int. Filing Date: **Aug. 6, 2024**

Int. Reg. No.: **DM/239279**

Int. Reg. Date: **Aug. 6, 2024**

Int. Reg. Pub. Date: **Aug. 23, 2024**

(30) **Foreign Application Priority Data**

Jul. 5, 2024 (CN) 202430419478.2

(51) **LOC (15) Cl.** **24-02**

(52) **U.S. Cl.**

USPC **D24/165**

(58) **Field of Classification Search**

Primary Examiner — Jennifer L Rempfer

Assistant Examiner — Edward P Jones

(57) **CLAIM**

The ornamental design for a blood pressure measuring apparatus as shown and described.

DESCRIPTION

1. Blood pressure measuring apparatus

1.1 : Front

1.2 : Back

1.3 : Left

1.4 : Right

1.5 : Top

1.6 : Bottom

1.7 : Front perspective view

1.8 : Back perspective view

The broken lines illustrate portions of the blood pressure measuring apparatus which form no part of the claimed design.

1 Claim, 8 Drawing Sheets
